(57) **CLAIM**

The ornamental design for a baseball set, as shown and described.

DESCRIPTION

FIG. 1 is a front, right and top perspective view of a baseball tee of baseball set, shown separately for ease of illustration; FIG. 2 is a rear, left and bottom perspective view thereof; FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged partial view of FIG. 1;

FIG. 10 is a front, right and top perspective view of a batting tee of baseball set, shown separately for ease of illustration;

FIG. 11 is a rear, left and bottom perspective view thereof;

FIG. 12 is a front view thereof;

FIG. 13 is a rear view thereof;

FIG. 14 is a left side view thereof;

FIG. 15 is a right side view thereof;

FIG. 16 is a top plan view thereof;

FIG. 17 is a bottom plan view thereof;

FIG. 18 is an enlarged partial view of FIG. 10; and,

FIG. 19 is a front, right and top perspective view of a baseball set. The broken lines in the figures illustrate portions of the baseball set that form no part of the claimed design. The dash-dot-dash lines shown in the drawings are for the purpose of showing the area of enlargement and form no part of the claimed design.
